UNITED STATES PATENT OFFICE.

RUDOLPH HOFFMAN, OF KANKAKEE, ILLINOIS, ASSIGNOR TO SEARS, ROEBUCK AND CO., OF CHICAGO, ILLINOIS, A CORPORATION OF NEW YORK.

OIL STOVE.

Application filed March 8, 1922. Serial No. 540,744.

To all whom it may concern:

Be it known that I, RUDOLPH HOFFMAN, a citizen of the United States, residing at Kankakee, in the county of Kankakee and 5 State of Illinois, have invented a certain new and useful Oil Stove, of which the following is a specification.

The invention relates to oil stoves or heaters having burners of the constant-level 10 type each comprising a burner bowl connected with a suitable source of oil supply and controlled by means adapted to vary the relative heights of the oil level and the burner bowl.

15 In wickless burner stoves as heretofore constructed and in general use, the oil is fed to the burner bowl from a horizontal supply pipe by means of an extensible pipe connection between the pipe and the bowl.

20 Such connection embodies a stuffing box intended to render the joint between the pipe sections oil-tight, but because of the peculiar tendency of the oil to creep by capillary attraction along metallic surfaces, 25 the stuffing box is ineffective. Various attempts have been made to overcome this difficulty among which was the use of a flexible connection between the supply pipe and the burner bowl. Such connections 30 were made from pipe of substantial length and then their flexibility was obtained by the insertion in the pipe of a large U-shaped part or diaphragm. This proved impractical because the end of the pipe connected 35 to the burner travelled in the arc of a circle. As a result, it was impossible with this construction to maintain the burner bowl in a true horizontal position and hence to obtain in the operation of the burner a 40 uniform and efficient flame.

A primary object of my invention is to overcome the difficulties above referred to by the provision of a means for conducting the oil from a fixed source of supply to the 45 burner bowl, which is, first, absolutely oil-tight and, second, which is capable of permitting the burner to be raised and lowered in a true vertical path and with a minimum expenditure of effort.

50 In attaining this object, I employ in my preferred construction a seamless metallic tube which is rendered readily flexible by spinning a helical groove in its outer periphery and collapsing the tube endwise so 55 as to bring the walls of the groove almost

together. While this tube is readily flexible so as to permit of easy up and down movements of the burner, I have found in practice that the tube has a tendency to bend only at the points adjacent its opposite ends 60 where it is connected on the one hand with the oil supply pipe and on the other hand with the pipe leading to the burner. Consequently these portions of the tube are subjected to undue strain and ultimately 65 crack or break and hence result in a leakage of the oil.

An important object of my invention is to provide an equalizing device adapted to distribute the strain upon the tube in the up 70 and down movements of the burner at least over a substantial portion of its length and, in the preferred form of my invention uniformly throughout the entire length of 75 the tube.

A further difficulty encountered with the flexible connections previously employed in burners of this type arose from the fact that the conductor extended in a generally horizontal direction directly from the burner bowl to the source of supply. Thus, it was found that when the burner was suddenly lowered, an objectionable flaring up of the flame occurred owing to the rush of oil under the action of gravity to the burner bowl, and the consequent generation of an excessive amount of vapor. A further object 80 of the present invention is to overcome this objection, and this is obtained by arranging the oil-conducting means so that the portion thereof communicating with the burner shall depend a substantial distance from the burner bowl, thus enabling the effectual control of the oil supply, causing it to be fed at 85 a uniform rate to the burner. 90

95 A further object of the invention is to provide improved means for mounting the burner for up-and-down movement.

Still another object of the invention is to provide improved means for indicating 100 the proper position of the burner with reference to the constant oil-level.

In the accompanying drawings, wherein I have illustrated a preferred form of my invention, Figure 1 is a side elevation partially in section of the improved burner. Fig. 2 is a front elevation of the burner. Fig. 3 is an elevational view, on an enlarged scale, of the flexible connection or conductor which permits of the vertical movements of 110

the burner with reference to a fixed source of oil supply, and showing the equalizing device thereon. Fig. 4 is a transverse sectional view taken on line 4-4 of Fig. 3. 5 Fig. 5 is a fragmentary detail view of a flexible metallic hose forming part of the oil conducting means.

In the drawings 7 designates generally one of a series of burners supported for 10 vertical movement beneath the top of a stove A and comprising an annular trough or bowl 8 which constitutes a receptacle for the oil and for a lighting ring (not shown) to facilitate the ignition of the oil. From 15 the bowl 8, a tubular stem 9 depends into operative relation with a support 10 embodying a tubular member or sleeve 11 with which a raising and lowering device 12 is adapted to coact. From the lower end of 20 the stem 9 a flexible conductor 13 leads in a generally horizontal direction to an oil supply pipe 14. The latter extends longitudinally of the stove and is connected by means of a pipe 15 with the well 16 of an oil 25 supply tank or reservoir 17. This well also constitutes an oil receptacle in which the level of the oil is maintained constant in a well known manner by the reservoir 17, and it will be observed that by effecting a 30 relative vertical movement between the receptacle or bowl 8 and the receptacle or well 16, the height of the flame may be varied at will. In the present instance, the receptacle 8 is raised and lowered by means of the 35 device 12 with reference to a constant oil level indicated in Fig. 1.

The burner 7 may be of any well known or preferred construction, comprising the 40 burner bowl 8 adapted to receive an annular lighting ring (not shown) and to support a chimney 18.

The stem 9 which depends from the trough 8 is rigidly secured to the trough at 45 the lower edge thereof, as by brazing, so as to provide a communication between the trough and the source of oil supply. The stem is made of substantial length and at its lower end enters a fitting 19 arranged for vertical movement within the support 10.

50 The support 10 comprises a bracket 20 of inverted U-shape having a front wall 21 and provided with flanges 22 by means of which the bracket is rigidly supported upon a longitudinal portion of the stove frame A. Rigid with the top portion of the bracket 55 is the member or sleeve 11 which is vertically disposed and adapted to neatly receive the stem 9 so as to guide the latter in its vertical movements.

60 For the purpose of enabling the raising and lowering device 12 to coact with the sleeve 11 and the stem 9, the sleeve is externally threaded as at 23 and the stem is provided with a fixed collar 24. Said device 65 125 has an internally threaded member

or nut 25 engaging with the screw threads 23 and having a pair of upstanding arms 26 shaped at their upper ends to engage with the member 24 which at its upper peripheral edge is provided with an annular rim or flange 27. The upper ends of the arms 26 are bent to form fingers 28 adapted to slidably engage with said flange 27 and at the upper ends of the arms, shoulders 29 are provided to engage with the underside 75 of the member 24. The nut 25 carries a plurality of arms 30 (herein three in number), each of which carry a radially extending handle 31. It will be seen that by the rotation of the member or nut 25 the 80 raising or lowering of the burner is effected.

The flexible pipe connection 13 extends directly between the lower end of the stem 9 and the feed pipe 14 in a substantially 85 horizontal direction. In its preferred form it comprises a normally straight seamless, metallic tube of relatively short length consisting of a plurality of relatively movable but non-slidable sections 32 together simulating bellows-diaphragms. These are formed by spinning a helical groove of substantial depth in a plain tube of suitable material, such as brass or copper of relatively light gauge, and then collapsing the tube endwise so as to bring the walls of the groove almost together as shown in Fig. 5. The result, it will be apparent, is the formation of a conductor having a plurality of helically shaped sections connected together but capable of relative movement to permit the bending or flexing of the conductor, and in such a way as to permit the burner bowl to be raised and lowered in a 90 true vertical path and hence maintained at 100 all times in horizontal position. Thus, it will be observed, one end of said conductor is attached to the fitting 19 in a manner hereinafter set forth; and the other end of the conductor is secured as by soldering 105 within a fitting 33 which communicates with the feed pipe 14. The opposite ends are therefore held rigid and in the up and down movements of the burner, the conductor tends to bend oppositely adjacent the fittings 110 19 and 33 as permitted by the relative movement of the sections 32 thereof.

The equalizing device which I employ for distributing the bending strain upon the flexible pipe comprises in the present instance a plurality of curved guide members 115 120 125 130 135 34 rigidly secured together at one end to the pipe and preferably arranged in pairs upon opposite sides of the pipe. In the present instance I employ two such pairs of guide members secured to the opposite ends of the pipe and curved outwardly so that their free ends are disposed a short distance away from the pipe as shown in Fig. 3. Preferably these guide members are semi-circular in 140

cross section (Fig. 4) so as to fit neatly around the pipe, and they are secured to the opposite ends of the pipe by being entered between the pipe and the fittings, 5 the opening in the latter being bored sufficiently larger than the pipe to accommodate the ends of the guide members. To secure the members in place in the fittings any suitable means may be employed, such, for 10 example, as solder.

As indicated clearly in Fig. 3, the guide members thus employed operate, as the burner is raised and lowered, to effect the uniform distribution of curvature and hence 15 strain throughout the length of the pipe. Thus it will be noted by reference to said figure, that in the extreme positions of the burner (indicated in broken lines) the degree of curvature of the pipe is substantially 20 the same at any point throughout its length. As a result, it is found in practice that the life of the pipe is prolonged to such an extent that under the most severe and trying 25 conditions the pipe connection will outlast the life of the stove.

The feed pipe 14 is stationarily mounted in any suitable manner in the stove frame A and carries upon its upper side the fittings 33 from which the flexible connections 13 30 lead to the several burners of the stove. Each of said fittings is secured upon the pipe 14 in any suitable or preferred way as by means of a clamp 37 encircling the pipe and having a screw 38 engaging the fitting.

35 For the purpose of indicating the various operative and inoperative positions of the burner, I provide an indicator comprising a pointer 51 carried by the fitting 19 (Figs. 1 and 2) and a scale formed on the front 40 wall 22 of the bracket 20. The pointer 51 is mounted upon a boss 52 on the fitting, as by means of a screw 53, a slot 54 being provided in the wall 21 of the bracket to receive the boss. The scale upon the wall 21 may 45 consist of suitable legends such as "Out", "Med.", "High" and "Light", stamped upon the forward face of the wall 21.

50 Preferably I provide means for enclosing the several flexible connections 13 of the stove, to prevent the accumulation thereon of dust and dirt which might interfere with the free flexing of the pipes. Herein this means is in the form of a sheet metal plate 55 suitably secured in position over the diaphragms 13. Preferably the plate extends 55 throughout the length of the stove and has at its forward end a downwardly extending flange 56 apertured to receive the forward end portion of the flexible conductor 13, and 60 resting at its lower edge upon a portion of the stove frame A which carries the bracket 20. At its rear edge the plate 55 may be secured to the frame A in any suitable way.

65 It will be apparent that I have produced an oil stove which is of a very practical

character. The burner is advantageously supported for up and down movement with the greatest facility. The flexible connection provided between the source of oil supply and the burner is of such a character as 70 to offer no material resistance to the up and down movements of the burner in a true vertical path, and the equalizing device ensures a long life for the feed pipe. By reason of the peculiar arrangement of the various 75 portions of the fuel conducting means, and especially of the stem 9, the supply of oil to the burner bowl 8 is effected in such a manner as to maintain the level of the oil constant, the action of gravity upon the oil 80 tending to cause an excessive flow when the burner is lowered, and hence an abnormally great vaporization as the oil strikes the heated burner bowl, being eliminated together with the resulting objectionable flaring up 85 of the flame. Finally the arrangement of parts is compact, and unsightly parts are concealed from view.

It is to be understood that while the invention is illustrated and described with considerable particularity, it is contemplated that various changes may be made in construction and arrangement without departing from the spirit and scope of the invention as expressed in the following claims. 90

This application is a continuation in part of my prior applications Serial No. 308,542 filed July 3, 1919; Serial No. 374,827 filed April 19, 1920 and Serial No. 527,538 filed January 7, 1922. 100

I claim as my invention:

1. An oil stove comprising, in combination with a source of oil supply, a constant-level oil burner having a burner bowl, a rigid upright tubular stem of substantial length 105 depending from the bowl, means for supporting the stem in various positions of vertical adjustment, and an approximately straight flexible conductor connecting the lower end of the stem with the source of oil 110 supply permitting of the vertical movement of the bowl.

2. In an oil stove the combination with a fixed source of oil supply, a constant-level oil burner, located at one side of the source of oil supply and comprising a burner bowl having a depending tubular stem of substantial length, a support having means for guiding the stem in its vertical movement, means for supporting the burner in various 120 positions of vertical adjustment, and an approximately straight flexible conductor between the lower end of the stem and the source of oil supply.

3. In an oil stove or heater, the combination of an upright oil supply stem, a supporting bracket having a tubular member of substantial length for guiding the stem for up and down movement, means coacting with said member and the stem to vary the 125

position of the stem vertically with reference to said support, and a conductor extending in a horizontal direction from said stem and including a flexible tube permitting the up and down movements of the stem.

4. In an oil stove or heater, the combination of an upright tubular oil supply stem, a support including a tubular guide for said stem, a member mounted upon said tubular guide and having a threaded engagement therewith, means carried by said member connecting it with said stem, and means for operating said member to effect the raising and lowering of the stem.

5. In an oil stove or heater, the combination with a burner bowl, and means connecting the burner bowl with a source of oil supply located at one side of the bowl, said means comprising an approximately straight conductor having a plurality of sections relatively movable so as to render the conductor flexible and permit relative up and down movement in a vertical path between the burner bowl and the source of supply.

6. In an oil stove of the class described, the combination with a burner bowl, means for raising and lowering the bowl in a vertical path, and means for connecting said bowl with a source of oil supply located at one side of the bowl including an approximately straight conductor having a plurality of sections movable with respect to each other in the up and down movements of the burner bowl with the latter at all times horizontal.

7. The combination of a burner of the class described, having a bowl with a depending tubular supply stem of substantial length and guided for vertical movement, means for raising and lowering the burner bowl, and means for connecting the lower end of the supply stem to a source of oil supply located at one side of the burner and comprising a substantially straight conductor having a plurality of sections relatively movable as the burner moves vertically.

8. In an oil stove, the combination with a stationary source of oil supply and an oil burner mounted for movement relative to said source of supply, of means providing a connection between said source of supply and the burner including a flexible metallic tube adapted to bend to permit such movements of the burner, and means operatively associated with said tube to distribute the bending strain upon the tube over a substantial length of the tube.

9. In an oil stove, the combination with a stationary source of oil supply and an oil burner mounted for movement relative to said source of supply, of means providing a connection between said source of supply and the burner including a flexible metallic

tube adapted to bend to permit such movements of the burner, and fittings with which the opposite ends of said tube are rigidly connected, one of said fittings being movable with the burner, and means adapted to engage with the end of the tube connected with the last mentioned fitting to distribute the bending strain on the tube due to the movements of the burner over a substantial length of the tube.

10. An oil stove of the class described comprising, in combination, a burner bowl, a supply stem depending from said bowl a substantial distance, means for supporting the bowl in various positions of vertical adjustment, a feed pipe located substantially in the plane of the lower end of said stem but spaced therefrom, a conductor between the lower end of the stem and said feed pipe consisting of a plurality of relatively movable sections adapted to render the conductor flexible, and means for enclosing said conductor to prevent the accumulation thereon of foreign matter such as to interfere with the relative movement between the sections.

11. An oil stove of the class described comprising, in combination, a burner bowl, a conductor between the burner bowl and said feed pipe consisting of a plurality of relatively movable sections adapted to render the conductor flexible, and means for enclosing said conductor to prevent the accumulation thereon of foreign matter such as to interfere with the relative movement between the sections.

12. In an oil stove, the combination with a burner bowl, an upright tubular stem depending from the bowl, means operable to effect the raising and lowering of the burner, an oil supply pipe, and a conductor connecting said pipe with the lower end of said stem, said conductor having a detachable connection with the oil supply pipe.

13. In a burner of the class described, the combination with a burner bowl and a fixed source of oil supply located at one side of the burner bowl, of means for raising and lowering the bowl in a vertical path so as to maintain the bowl horizontal, and means for connecting said bowl with the source of oil supply including a fitting connected with the bowl and a horizontally disposed metallic conductor having a plurality of sections movable with respect to each other so as to be capable of flexing adjacent said fixed source of supply and also adjacent said fitting.

14. In an oil stove, the combination of a frame, a feed pipe stationarily mounted rearwardly in the frame, a burner located forwardly of the frame and comprising a burner bowl guided for up and down movements in a vertical path, and means connecting the feed pipe with the burner in-

- cluding a normally straight tube of relatively short length flexible at each end to permit such vertical movement of the burner.
- 5 15. In an oil stove or the like, the combination with a stationary source of oil supply, a burner guided for vertical movements, and means providing a connection between the burner and the source of supply including a tubular member having the end adjacent the burner extending in a generally horizontal direction and capable of bending at said end to permit the vertical movements of the burner.
- 10 16. In an oil stove, the combination with a supply pipe, an annular burner bowl guided for vertical movement and having depending from its forward edge a tubular supply stem and a flexible conductor connecting the lower end of said stem with said supply pipe, said conductor being of relatively short length and extending beneath the burner bowl approximately in a straight horizontal direction.
- 15 17. In an oil stove, the combination with a stationary source of oil supply, a burner mounted for movement relative to said source of oil supply, and a connection between the burner and said source of supply including a flexible metallic tube disposed throughout its length in a horizontal plane, said tube being constructed to render it flexible at any point in its length.
- 20 18. In an oil stove or the like the combination with a stationary source of oil supply and a burner bowl mounted for relative vertical movement, and a connection between the burner bowl and said source of supply, said connection including a normally straight flexible metallic tube constructed to bend in opposite directions at spaced points in its length in such vertical movement of the bowl.
- 25 19. The combination with a source of oil supply, a burner, and means connecting the burner with the source of supply to permit of relative up and down movement therebetween; of means for effecting such up and down movement including an upright stationary guide stem, a movable member slidably engaging in said stem, and a part threaded upon said stem and having an operative connection with said member whereby in the rotation of said part movement is imparted to said member.
- 30 20. In a stove or heater, the combination with an oil receptacle, an upright tubular stem depending from the receptacle, a support for the stem comprising a bracket, a tubular guide member rising from the bracket for the stem, means coacting with said guide member and said stem to effect the raising and lowering of the stem, and indicating means carried by the stem.
- 35 21. The combination with a source of oil supply, a burner, means providing a connection between the burner and a source of oil supply including a horizontally disposed flexible tube adapted to permit the burner to move vertically, and means for effecting such vertical movement of the burner including a vertical guide stem, a movable member slidably engaging said stem and rigid with said burner, a part having an operative connection with said member, and means adapted upon the rotation of said part to effect the up and down movements thereof of said member.
- 40 22. In a stove of the class described, the combination of a burner bowl, a stem depending from the bowl, a support including a tubular guide for said stem, a member mounted upon said tubular guide for up and down movement, means carried by said member operatively connecting it with said stem, means for rotating said member to effect the up and down movement thereof and of the burner bowl, and means for conducting a supply of oil to said bowl including a flexible conductor communicating with the source of oil supply and the burner bowl.
- 45 23. In a stove or heater, the combination with a burner including a receptacle and a source of oil supply including a second receptacle, horizontally spaced from the first receptacle, of means for raising and lowering one of the receptacles, means for connecting said receptacles including an approximately straight conductor formed from seamless tubing and having a plurality of relatively movable sections to render it readily flexible, and means for enclosing said conductor.
- 50 24. In an oil stove or the like, the combination of a fixed source of oil supply, a burner, means for conducting oil from said source of supply to the burner including a seamless metallic tube adapted to permit of the relative up and down movement between the burner and the source of supply, and means acting upon one end of the tube to distribute the bending strain over a substantial length thereof.
- 55 25. In an oil stove or the like, the combination of a burner bowl, a source of oil supply, means including a flexible metallic tube connecting said burner bowl with the source of oil supply and adapted to permit of the relative up and down movement between the burner bowl and the source of supply, and an equalizing device for distributing the bending strain upon said tube substantially uniformly throughout the length thereof.
- 60 26. In an oil stove or the like, the combination of a source of oil supply, a burner, means for conducting oil from said source of supply to the burner including a seamless metallic tube adapted to permit of relative up and down movement between

the burner and the source of supply, and means acting upon one end of the tube to distribute the bending strain over a substantial length thereof, the last mentioned means including a curved guide member rigid with one end of the tube.

27. In an oil stove or the like, the combination with a burner, of means for conducting a supply of oil to the burner including a rigid fitting and adapted to permit of the up and down movements of the opposite end of the pipe, a flexible feed pipe connected at one end with the fitting, and means for distributing the bending strain upon said pipe adjacent the fitting over a substantial length of the pipe.

28. In an oil stove or the like, the combination with a burner, of means for conducting a supply of oil to the burner including a rigid fitting and adapted to permit of the up and down movements of the opposite end of the pipe, a flexible feed pipe connected at one end with the fitting, and means for distributing the bending strain upon said pipe adjacent the fitting over a substantial length of the pipe, said means including a guide member secured at one end to the fitting and gradually curving outwardly toward its opposite end.

29. In an oil stove or the like, the combination with a burner, of means for conducting a supply of oil to the burner including a flexible feed pipe, a pair of fittings one at each end of said pipe, means for effecting relative up and down movement between said fittings, and means at the opposite ends of the pipe for distributing the bending strain normally occurring adjacent said fittings over a substantial length of the pipe.

30. In an oil stove or the like, the combination with a burner, of means for conducting a supply of oil to the burner including a flexible feed pipe, a pair of fittings one at each end of said pipe, and means at the opposite ends of the pipe for distributing the bending strain normally occurring adjacent said fittings over a substantial length of the pipe, said means including two pairs of guide members, the members of each pair being secured to one of the fittings upon opposite sides of the feed pipe and extending a substantial distance toward the center of the pipe and gradually curved outwardly away from the pipe.

31. The combination of a burner having a burner bowl, a source of oil supply located at one side of the burner, a feed pipe rigid with the burner and depending therefrom, a flexible tube connecting the lower end of said pipe with the source of oil supply, and combined means for guiding the burner for up and down vertical movements and for effecting such movements including a stationary vertical member, and a part slideable on said member and having an oper-

ative connection with the feed pipe, said part being adapted when rotated to move vertically on said member.

32. The combination of a burner having a burner bowl, a source of oil supply located at one side of the burner, means providing a connection between the burner bowl and said source of supply adapted to permit of the up and down movements of the burner, said means comprising a pipe rigid with the burner bowl and depending vertically therefrom, and combined means for guiding said pipe and thereby said burner for vertical movement and for effecting such movement, the last mentioned means comprising a guide member adapted slidably to receive said pipe, and a part operatively associated with said member and said pipe and rotatable on an axis coaxial with that of the pipe whereby to raise and lower the pipe in said member.

33. An oil stove having a burner, an oil pipe located at one side of the burner, means operable to raise and lower the burner in a vertical path, and means for supplying oil from said source of supply to said burner including a tube having one end rigid with respect to the burner and its other end rigid with respect to the source of supply and extending in an approximately horizontal direction, said tube being constructed so as to be capable of bending reversely near its opposite ends from a normally straight form to a reversely curved form as the burner moves vertically from one elevation to another.

34. The combination of a source of oil supply and a burner mounted for relative up and down movement, means connecting the source of supply with the burner permitting of such movement, and means for effecting such up and down movement including a stationary upright stem, a collar fixed with reference to the part to be moved, a rotary member threaded on said stem and having means slidably engaging with said collar for circumferential movement only, and means for rotating said member.

35. The combination with a vertically movable receptacle, of raising and lowering means comprising a collar fixed with reference to the receptacle, a stationary upright stem and a rotary member threaded on said stem and having a pair of spring arms slidably engaging said collar for movement circumferentially thereof only.

36. The combination with a vertically movable receptacle and means for raising and lowering the receptacle comprising a part depending therefrom, a stationary support, an upright member on said support, adapted to coact with said depending part to guide the receptacle for vertical movement and a rotary member operatively engaging said upright member and said

depending part whereby in the rotation of the rotary member the receptacle is caused to move up or down

37. An oil stove or the like having, in combination, a vertical tubular member, a hand wheel having a screw-thread connection with said member, an oil receptacle, a rotatable connection between the receptacle and the hand wheel, and means to prevent 10 the receptacle from turning.

38. In an oil stove or the like, the combination of a vertical tubular member, a second member guided for vertical movement with respect to the first member, one 15 of said members being externally screw-threaded and having a nut thereon and the other one of said members having a collar fixed thereon, and means connecting said nut and collar whereby in the rotation of 20 the nut relative vertical movement is effected between said members.

39. In an oil stove or the like, the combination of a vertical tubular member, a second member guided for vertical movement with respect to the first member, one 25 of said members being externally screw-threaded and having a nut thereon, and the other one of said members having a collar fixed thereon, and means connecting said 30 nut and collar whereby in the rotation of the nut relative vertical movement is effected between said members, the movable one of said members constituting an oil supply pipe, and means connecting said pipe with a 35 receptacle including a flexible tube.

40. In an oil stove, the combination with a stationary source of oil supply, a burner mounted for movement relative to said source of oil supply, and a connection 40 between the burner and said source of supply including a flexible metallic tube, said tube being constructed from a seamless metallic pipe having its periphery grooved to form contiguous sections capable of moving relative to each other.

41. In an oil stove, or the like, the combination with a stationary source of oil supply and a burner mounted for relative vertical movement, and a connection between the burner and the source of supply including a flexible metallic tube disposed horizontally throughout its length and constructed to bend in opposite directions at spaced points in its length in such vertical movement between the burner and the source 50 of supply. 55

42. In an oil stove, the combination with a fixed source of oil supply, a burner comprising a burner bowl having a depending tubular stem of substantial length, a support 60 having means for guiding the stem in its vertical movement, means for supporting the burner in various positions of vertical adjustment, and a flexible conductor between the lower end of the stem and the source of oil supply. 65

43. In an oil stove, the combination with a frame, a feed pipe stationarily mounted rearwardly in the frame, a burner located forwardly of the frame and comprising a burner bowl, an upright tubular stem depending from the bowl, means flexibly connecting the feed pipe with the lower end of the stem so as to permit of the vertical movement of the latter, and means for raising 70 and lowering the burner. 75

44. In an oil stove, the combination with a frame, a feed pipe stationarily mounted rearwardly in the frame, a support stationarily mounted forwardly in the frame, a 80 guide member on said support, a burner bowl having a tubular stem depending through said guide member, means connecting the lower end of the stem with the feed pipe so as to permit of the vertical movement of the stem, and means for raising and lowering the burner bowl. 85

In testimony whereof, I have hereunto affixed my signature.

RUDOLPH HOFFMAN.
